UNITED STATES PATENT OFFICE

FRANK E. KEESE, JR., OF IRON RIVER, MICHIGAN

COMBINATION FUSE HOLDER AND LIGHTER

Application filed April 21, 1932. Serial No. 606,711.

This invention relates to combined fuse holders and lighters and has for the primary object, the provision of a device of the above stated character which is especially adapted 5 for receiving and holding a plurality of explosive fuses regardless of their lengths and having an igniting medium which when lighted will be slow burning and will successively ignite the fuses in accordance with 10 the arrangement thereof in the holder to assure lighting of all of the fuses with maximum safety to the operator and permit the operator to easily reach a point of safety or shelter prior to the explosion.

15 With this and other objects in view, this invention consists in certain novel features of construction, combination and arrangement of parts to be hereinafter more fully described and claimed.

20 For a complete understanding of my invention, reference is to be had to the following description and accompanying drawing, in which

Figure 1 is a plan view illustrating a combined fuse holder and igniter constructed in accordance with my invention.

Figure 2 is an edge elevation illustrating the same with the igniter removed.

Figure 3 is a sectional view taken on the 30 line 3-3 of Figure 2.

Figure 4 is a transverse sectional view taken on the line 4-4 of Figure 1.

Figure 5 is a similar view taken on the 35 line 5-5 of Figure 1.

Figure 6 is a fragmentary sectional view taken on the line 6-6 of Figure 1.

Referring in detail to the drawing, the 40 numeral 1 indicates a holder comprising a pair of relatively spaced plates 2 which have their ends offset inwardly and secured together by rivets 3. Rightangularly extending flanges 4 are formed on the edges of the plates and the flanges of one plate extend in corresponding direction and in opposite directions to the flanges of the other plate. Hooks 5 are carried by the ends of the holder and removably support an igniting medium 6 preferably constructed from a slow burning composition. The igniting medium is 45 flattened throughout a portion thereof and

disposed opposite one edge of the holder while the remaining portion of the igniting medium is of rod shape and projects a considerable distance beyond one end of the holder for the purpose of being ignited by the operator. The rod shaped portion of the igniting medium is comparatively slow burning, while the flattened portion of the igniting medium is capable of producing sufficient flame to assure the igniting of fuses 7 carried by the holder.

Retaining tongues 8 are struck inwardly from the plates 2 and have their free edges serrated as shown at 9 for the purpose of permitting the fuses 7 to be readily inserted between the plates but which will prevent accidental removal of the fuses from the holder due to the serrations biting into the fuses as shown in Figure 4. By referring to the drawing it will be seen that a plurality of fuses may be accommodated within the holder and that the fuses can be secured in place to be ignited by the burning of the ignition medium regardless of their lengths.

For a number of years it has been common 75 practice in mining work to use safety fuses and blasting caps to fire or ignite high explosives. The fuses are cut in different lengths so that the charged holes will be exploded in the order wanted and as it is necessary that the center or "cutting in" holes explode before the others, the lengths of the fuses for these holes are naturally shorter than the others. The lengths of all fuses, however, must be long enough to allow the 80 operator after lighting the ignition medium sufficient time to seek shelter from the blast, the burning speed of ordinary fuses being approximately two feet per minute, and it will be readily seen that the shortest fuses 85 cannot safely be less than three feet in length which allows thirty seconds for lighting the fuses and then one minute for the operator to reach a place of safety, however, in many instances a greater time should be afforded 90 the operator to reach a point of safety and which can be easily accomplished by increasing the lengths of the fuses. The ends of the different fuses are placed in the holder in the order that the holes are to be fired, 95 100

in other words, the shortest fuses are placed in the holder at the end where the fire from the igniting medium will strike first, the other fuses being placed beyond the shortest one in the order of firing and in this way the fuses for the "cutting in" holes are lit before the others and due to the different lengths of the fuses they will fire the explosives in the order desired. A device of this character provides maximum safety and permits one person to light several times the number of holes than formerly and with maximum safety. It is to be understood that the holder may be varied in length to suit various mining conditions wherein the number of fuses employed vary.

While I have shown and described the preferred embodiment of my invention, it will be understood that minor changes in construction, combination and arrangement of parts may be made without departing from the spirit and scope of my invention, as claimed.

Having thus described my invention, what I claim is:

1. A holder comprising spaced plates fixed together to receive therebetween a plurality of fuses with their igniting ends arranged in alignment, tension tongues on said plates and gripping the fuses, and a burnable medium carried by said plates and arranged in close proximity to the igniting ends of said fuses.
2. A holder comprising spaced plates fixed together and receiving therebetween a plurality of relatively spaced fuses with their igniting ends exposed and arranged in alignment with each other, resilient tongues struck from said plates and having serrated edges to bite into the fuses, and a slow burnable medium carried by said plates to ignite the fuses.
3. A holder comprising spaced plates fixed together and receiving therebetween a plurality of relatively spaced fuses with their igniting ends exposed and arranged in alignment with each other, resilient tongues struck from said plates and having serrated edges to bite into the fuses, hooks carried by the ends of said plates, and a slow burnable medium removably supported by the hooks lying in close proximity to the fuses and projecting a desirable distance beyond one end of said plates to be ignited.

In testimony whereof I affix my signature.

FRANK E. KEESE, Jr.
